UNITED STATES PATENT OFFICE.

EDWARD AUGUSTUS RIDER, OF WESTBURY, NEW YORK, ASSIGNOR OF ONE-HALF TO
LILLIAN R. MOSHER, OF WESTBURY, LONG ISLAND, NEW YORK.

AERO SUBMARINE TORPEDO.

1,337,960.

Specification of Letters Patent. Patented Apr. 20, 1920.

Application filed August 21, 1917. Serial No. 187,342.

To all whom it may concern:

Be it known that I, EDWARD AUGUSTUS RIDER, a citizen of the United States, and a resident of Westbury, in the county of 5 Nassau and State of New York, have invented a new and Improved Aero Submarine Torpedo, of which the following is a full, clear, and exact description.

This invention relates to torpedoes and 10 has particular reference to high explosive devices adapted particularly for dropping from aeroplanes in attacks upon submerged submarines.

Among the objects of the invention is 15 to provide a torpedo comprising a body with a heavy point and having its base portion charged with an explosive and equipped with means which after the torpedo enters the water will have a tendency to retard 20 the speed of the projectile.

Another object of the invention is to provide a projectile calculated to be delivered from a high elevation in the air and equipped with means for automatically causing the 25 rotation of a certain portion in a certain direction due to the movement through the air and having means for retarding and then reversing the speed of such part after the projectile enters the water for the purpose of effecting the firing of the charge at 30 a certain substantially determined depth beneath the surface of the water.

Another object of the invention is to provide a torpedo designed to be delivered at 35 a high altitude in the air for the object of plunging into the water, the device being provided with means operated automatically by movement through the atmosphere for insuring that the torpedo shall travel 40 in a substantially straight course without tumbling and the same means serving to initiate a rotary movement of a certain portion of the device at high speed while passing through the air, said automatic means, 45 however, being calculated to be rendered inoperative when striking the water.

With the foregoing and other objects in view the invention consists in the arrangement and combination of parts hereinafter 50 described and claimed, and while the invention is not restricted to the exact details of construction disclosed or suggested herein, still for the purpose of illustrating a prac-

tical embodiment thereof reference is had to the accompanying drawings, in which like 55 reference characters designate the same parts in the several views, and in which—

Figure 1 is a vertical longitudinal section of my improvement with the movable parts in firing position. 60

Fig. 2 is an enlarged view of the base portion of my improvement showing more particularly the manner of construction and assemblage.

Fig. 3 is a view corresponding to Fig. 2, 65 but with the movable parts in position in which they are set preparatory to the delivery of the device from a high altitude or the position which the parts occupy while moving through the air. 70

Fig. 4 is a sectional detail on the line 4—4 of Fig. 3; and

Fig. 5 is a transverse sectional detail on the line 5—5 of Fig. 2.

Referring now more particularly to the 75 drawings I show a torpedo comprising a body 10 having a solid or weighted pointed end 11 and a relatively hollow base portion 12. This body portion 10 is substantially straight except where it tapers into the 80 weighted end and may be of any suitable form in cross section. The cavity 12 may be of any suitable extent longitudinally of the device, but indicated herein as substantially coextensive with the base half of the 85 device. The main or central portion of this cavity is filled with any suitable high explosive 13 held within a shell or hollow cylinder 14 having flanges 15 and 16 at its upper and lower ends serving to hold the 90 main portion of the shell spaced inwardly from the inner wall of the cavity 12. This space between the shell and the cavity wall is designed to be filled with balls 17 or the like. 95

To the base end of the body (otherwise referred to herein as the upper end) is secured a head 18 by any suitable means making a positive and fixed connection after the parts are assembled. This head has a 100 central hole into which is tapped at 19 the neck portion 20 of a collar member 21 having a shoulder 22 fitted against a flange 23 immediately surrounding the hole 19. A nut 24 is fitted upon the outer end of the 105 neck 19 and serves to lock the collar in fixed

position in the head. The lower end of the collar projects into the cavity 12 of the body and is surrounded by the explosive 13.

The extreme lower end of the collar is fitted with a stationary cap 25 shown as threaded thereupon and having a central hole or port 26. This cap is surrounded by a relatively small quantity of quick explosive 27, the same being held within a bag 10 or casing 28 surrounding the cap 25.

The upper end or surface of the head 18 is recessed or dished at 29, the nut 24 being located entirely within this recess.

At 30 I indicate a spindle journaled for free rotation in one direction within the collar 21 around the central axis of the entire device. The lower end of the spindle lies close to the cap 25 and has a port 31 registering with the port 26 and adjacent to which is located a primer 32. This end of the spindle is connected with the sleeve through anti-friction bearings 33. The outer surface of the lock nut 24 is provided with a raceway for anti-friction balls 34 with which cooperates a bearing ring 35 threaded upon the upper end of the spindle and locked in position by means of a lock nut 36, the ring and the nut last mentioned being both located within the recess 29 and below the plane of the upper edge of the head 18. The bearings 33 and 34 insure the adaptability of the spindle for free rotation within the limits contemplated by this invention. Next adjacent to the lock nut 36 are fitted upon the upper end of the spindle two propellers 37 and 38, the former being just about one half within the recess 29 and the other half above the recess, but with the blades not projecting beyond the recess laterally so that while the torpedo is traveling through the air the propeller 37 will be functionless. The blades of the other propeller, however, extend laterally far beyond the head 18. The blades of the two propellers are reversely arranged, that is to say, with the blades of the propeller 38 arranged as indicated, the latter may serve to rotate the spindle and the other parts connected thereto at high speed in a counter clock-wise direction as viewed by the person who delivers the same from the aeroplane or other elevated position, while the blades of the smaller lower propeller 37 are arranged so as to tend to rotate the spindle in an opposite or clock-wise direction. These propellers, however, are both fixed to the spindle, as for example, by means of their threaded hubs and outside lock nut 39. The upper propeller 38 being larger than the lower and being more fully exposed to the air obviously will predominate over the lower propeller while passing through the air and hence will cause the positive rotation of the spindle in a left or counter clock-wise direction. The blades, however, of the upper propeller are calcu-

lated to snap off, being made of wood or other breakable material, when the torpedo strikes the water the impact of the water being so much more severe upon the blades than the resistance of the atmosphere. It will now be seen, therefore, that the propeller 38 will serve to rotate the spindle in one direction within the collar 21 carrying the propeller 37 therewith in a direction opposed to the direction of the latter and that the propeller will tend to be rotated by the medium through which the device is passing. When the propeller blades 38 are broken off the propeller 37, by virtue of the direction of rotation imparted to it, while the device is passing through the air, will so act upon the water as to retard and stop the rotation of the spindle before the device travels many feet through the water. It is not intended for the propeller 37 to stop the torpedo and, therefore, while the torpedo continues to move through the water after the rotation of the spindle has momentarily ceased, the water acting upon the propeller 37 will finally cause said propeller to rotate in a clockwise direction as indicated by the arrow on Fig. 5.

The spindle is centrally and longitudinally bored at 40 to receive a two part lining 41. The lower end of this lining is designed to hold the primer 32 which is projected into an extension 40' of the bore 40. In the upper end of the lining is fitted a bearing block 42 in which is adapted to reciprocate a firing pin 43 having a knob 44 at its upper end and an annular groove 45 surrounding the same at a slight distance below the knob. A plug 46 is tapped into the upper end of the spindle which holds the lining and bearing block in fixed position, the outer end of the block being flush with the upper end of the spindle. A strong expansion spring 47 is coiled around the firing pin between the bearing block 42 and the lower end of the pin which is calculated to impinge against the primer when the spring 47 is permitted to be expanded.

In setting the device preparatory for delivery the operator grasps the knob 44 and draws the firing pin upward against the force of the spring 47 until the groove 45 appears above the block 42, at which time a keeper 48 will snap into the groove 45 under the force of a resilient rocker 49 located in a double tapered channel 50 formed longitudinally in one side of the spindle. The keeper 48 is held from radial sliding movement with respect to the axis of the firing pin as by means of pins or screws 51 extending through parallel slots 52 formed in the keeper. See Fig. 4. The channel 50 and the rocker 49 are so designed as to cause the keeper to remain or tend to remain in the groove 45 to hold the firing pin in set position. As it will be noted especially in

70

Fig. 3, the rocker 49 acts in the nature of a lever of the first class with the fulcrum thereof at the narrowest portion of the channel 50 and with the lower end of the lever projected through the keeper 48. I provide also an auxiliary or safety keeper 53 adapted to be manipulated by the operator on the opposite side of the firing pin and coöperating with the same groove 45 when it is desired to positively insure the device against premature discharge. Obviously, however, when the device is delivered for effective operation the trigger 53 is withdrawn from the firing pin.

The lower end of the channel 50 communicates with or merges into a pit 54 which lies, generally speaking, in a plane perpendicular to the axis of the torpedo. The side walls of the pit may be defined by vertical planes which converge and meet outside of the spindle. In other words the pit is of approximately triangular form as viewed in plan in Fig. 5 and where the planes of the side walls thereof intersect the surface of the spindle there is formed an opening in which is located a dog 55 having a stem 56 slidably fitted in a sleeve 57 located in the pit against the outer wall thereof. The lower end of the rocker 49 bears normally against the inner end of the sleeve 57 and holds the sleeve in the position indicated. A spring 58 acts normally upon the dog to hold the dog projected or so that it may be projected into one of several notches 59 formed in the inner wall of the collar 21. The movement, however, of the dog is limited by means of a pin 60 extending loosely through the sleeve and stem 56 and spanning the pit 54. While the spindle is being rotated in counter clock-wise direction by operation of the propeller 38 the dog will be forced inwardly against the spring 58 by reason of the rounded outer face of the dog riding against the inner wall of the collar and no material resistance will be set up thereby tending to interfere with such rotation. When, however, the blades of the propeller 38 are broken off and the other propeller 37 effects a reverse rotation of the spindle as above set forth the dog will immediately enter one of the notches 59, the point of the dog striking against the undercut shoulder at the end of the notch which will act as a fulcrum while the force of the propeller will tend to rotate the spindle and trigger devices in the direction of the arrow on Fig. 5. (The collar 21 and the device as a whole having no rotation around its axis). The inner end of the sleeve will be forced radially toward the center of the firing pin carrying with it the lower end of the rocker and causing the withdrawal of the keeper 48 from its holding position, thus setting free the firing pin.

It is contemplated that the character of the explosive, if fired at any reasonable distance from the submarine, will have the effect of wrecking the same. If, however, the torpedo strikes the submarine prior to the explosion of the torpedo the submerged vessel will be destroyed whether the torpedo explodes or not.

I claim:

1. The herein described torpedo comprising a body having a cavity, an explosive in the cavity, firing devices to ignite the explosive, said firing devices including a member adapted to rotate, means connected to the member to cause rotation thereof in one direction during a portion of the travel of the torpedo, and other means connected to the member to cause rotation thereof in the opposite direction during another portion of the travel of the torpedo.
2. The herein described torpedo designed to be delivered from a high altitude to be exploded beneath the surface of the water, the same comprising a body, an explosive carried within the body, firing devices calculated to ignite the explosive beneath the surface of the water, said firing devices including a member adapted to rotate around an axis parallel to the path of the torpedo, means to rotate said member in one direction while passing through the air, means to rotate said member in the opposite direction after the torpedo enters the water, and trigger devices so arranged as to effect the firing of the explosive only as a result of the torpedo entering the water.
3. In a torpedo designed to be delivered through the air for explosion beneath the surface of the water, the combination of a body having a cavity, an explosive carried within the cavity, a head fixed upon the body and holding the explosive in place, a rotary member journaled in said head, firing devices for the explosive carried in and rotatable with the spindle, and means connected to the end of the spindle outside of the head serving to cause rotation of the spindle in opposite directions in alternation.
4. In a torpedo of the class set forth, the combination with a body having a cavity, an explosive carried in the cavity, a bearing collar fixed to the body, a spindle journaled in and extending through the collar, firing devices for the explosive carried by the spindle, means acting upon the spindle to cause successive rotation thereof in opposite directions before and after the torpedo enters the water, and means whereby the rotation of the spindle in the collar in one direction will effect the firing of the explosive, while the rotation of the spindle in the opposite direction is without such effect.
5. In a torpedo, the combination of a body having a cavity, an explosive in the cavity, a closure for the cavity holding the

- explosive in place, a bearing member fitted in the closure and held from rotation with respect to the body, a spindle journaled in the bearing member, firing devices associated with the spindle, and means connected to the spindle to effect the rotation thereof in the firing direction after the torpedo enters the water, such effect resulting from the fact of the same entering the water.
6. In a torpedo, the combination with a body, an explosive within the body and firing devices for the explosive including a movable member, means connected to the movable member tending to operate the same in opposite directions, a portion of such moving means being effective while the torpedo is moving in the air, but being destroyed when the torpedo strikes the water when the other moving means becomes active, and trigger devices made operative by the reversal of movement of said movable member.
7. In means for firing torpedoes, the combination of relatively fixed and rotary members, a pair of propellers fixed to the rotary member and calculated to rotate the same in opposite directions, one propeller being larger than the other and effective while the torpedo is moving through the air, and being functionless after the torpedo strikes the water permitting the other pro-

peller to operate, and trigger devices made operative by reversal of movement of the rotary member.

8. In a torpedo, the combination of a torpedo, a head fixed to the body, an explosive within the body, the head having an exterior recess, a spindle journaled in the head coaxially with said recess, a propeller fixed to the outer end of the spindle and projecting beyond the head whereby the spindle is adapted to be rotated in a certain direction, another propeller fixed to the spindle between the larger propeller and the head and projecting into the recess, the latter propeller tending to rotate the spindle in the opposite direction after entering the water, and trigger devices for firing the explosive as a result of the reversal of movement of the spindle.

9. In a torpedo, the combination of a body, a head fixed to the body, an explosive within the body, a spindle journaled for rotation in the head, means to rotate the spindle at high speed while the torpedo is passing through the air, means connected to the spindle to automatically retard and then reverse the rotation thereof after the torpedo enters the water, and trigger devices to fire the explosive as a result of such reversal of rotation of the spindle.

EDWARD AUGUSTUS RIDER.
